Primary Examiner — T Chase Nelson*Assistant Examiner* — Sydney Margaret Parsley(74) *Attorney, Agent, or Firm* — Thedford I. Hitaffer; Hitaffer & Hitaffer, PLLC(57) **CLAIM**

I claim the ornamental design for a hunting saddle, as shown and described.

DESCRIPTION

FIG. 1 is a perspective view of a hunting saddle, from the front, left, and bottom, showing the new design.

FIG. 2 is a perspective view thereof, from the front, right, and bottom.

FIG. 3 is a perspective view thereof, from the front, right, and top.

FIG. 4 is a perspective view thereof, from the front, left, and top.

FIG. 5 is a bottom view thereof.

FIG. 6 is a top view thereof.

FIG. 7 is a right side view thereof.

FIG. 8 is a left side view thereof.

FIG. 9 is a front view thereof; and,

FIG. 10 is a rear view thereof.

In the drawings, the broken lines shown in the figures depict unclaimed subject matter and form no part of the claimed design.
